BRAKE CONNECTION

William J. McDonald, Chicago, Ill., assignor, by
mesne assignments, to Pullman Car & Manufacturing Corporation, a corporation of Delaware

Application November 28, 1930
Serial No. 498,572

4 Claims. (Cl. 74—17)

The invention relates to brake connections for use in vehicle braking systems, and particularly the connecting bars for the levers of such systems.

5 Connecting bars for this purpose have usually been fashioned complete from a single plate or bar manipulated to provide all of the jaws and the body of the connection.

This invention contemplates the use of a pair 10 of bars of constant cross section welded at their respective edges to provide a unitary hollow member of predetermined length and strength, the ends of the bars being severally forged to provide connection jaws.

15 The principal object of the invention is to provide a rugged connecting bar so designed as to permit the use of commercial rolled bars of angular or curved cross-section, if desired.

The foregoing and other objects are attained 20 by the mechanism illustrated in the accompanying drawing, in which

25 Figure 1 is a plan view of a preferred embodiment of the invention, with a portion of the connecting bar at the jaws broken away to show the disposition of the pin openings and the jaw material;

Figure 2 is a side elevational view of the same 30 with the jaw of one of the bars of the connection broken away to expose the inner face of the companion jaw on the other bar;

Figure 3 is a section thru the jaws taken on line 3—3, of Figure 2, and slightly enlarged to show the distribution of the jaw metal;

Figure 4 is a similar section thru the body of 35 the assembled connecting bar taken on line 4—4, of Figure 1, showing the method of welding the bar members;

Figure 5 is a view similar to Figure 2, but showing the members of curved cross-section; and

40 Figure 6 is a view similar to Figure 1 but showing the jaws disposed with their pin opening bosses extruded outwardly.

In the drawing, 10 represents the connecting bar as a whole made up of two complementary 45 angle plates 11 united by welds 12 spaced apart as shown or by continuous weld, as desired. The contiguous bar edges 13 combine to form grooves 14 designed to accommodate the welds 12 as best shown in Figures 1, 3, and 4. To form the 50 jaws 15, the corners or crests 16 of the angles and adjacent flanges 17 are deformed by forging to provide a relatively flat web portion 18 having a circumscribing peripheral flange portion 19 and extruded flange portions 20 defining pin openings 55 21 to provide extended bearing areas for the con-

nexion pins. Where commercial rolled angle bars are used as shown, the corners 16 and fillet metal 22 thereof extend into the jaw area and supplement the material entering the jaw to rigidify the body portion of the connection and 60 basal extremities of said jaws.

The jaws 15 are arranged parallel to the weakest neutral axes X—X of the severed bars and take their respective load thrust outside the plane of said axes, whereby such thrusts are imposed eccentrically to cause said members to be stressed toward each other. By this arrangement the pressures exerted are balanced and the tendency of the bar assembly to buckle under compression is reduced to a minimum. 70

With the contiguous flange edges 13 in extended bearing engagement with each other as indicated in Figures 1, 3, and 4, the welds 12 function only to prevent separation of the bars between the jaws and to further rigidify the assembly. In the preferred embodiment illustrated 75 in the first four figures of the drawing, the web portions 18 of the jaws 15 are disposed outwardly of the extruded metal portions 20 along the jaw peripheries and about the pin openings 21, and in substantial alinement with portions of the members farthest removed from the neutral axis of the assembly. 80

The jaws 15 may take the form depicted in Figure 6 in cases where additional bearing area 85 for the brake lever is deemed necessary. As shown, the web portions 18 of the jaws are disposed inwardly of the extruded reinforcing portions 19 and 20, and in substantial alinement with the weakest neutral axis X—X of the respective members. 90

It may be desirable at times to substitute curved plates for the angle plate sections of the preferred embodiment. As shown in Figure 5, pressed or rolled bars 23 of semicircular or crescent shape are placed together edge to edge to form a tubular column and united by welding as in the case of the angular bars. The ends of the respective bars are manipulated to form jaws 24 with extruded pin bearing flanges 25 and peripheral stiffening flanges 26 projecting from either side of the web portions 27. 100

Although the jaw structures have been described as having their respective web portions inwardly or outwardly of their extruded flange 105 portions it is obvious that the jaw sections may assume a general I-beam configuration with the several webs positioned midway of the extruded flanges defining the pin openings and jaw peripheries, and also function to transmit the load 110

thrusts outside the plane of the weakest neutral axes of the members to stress the bars towards each other as in the case of the other embodiments.

- 5 A connecting bar of the type described may be economically produced from prepared sections or members fabricated to suit and united by electrically welding them, preferably in a jig to insure accurate alinement of the pin openings in 80
10 companion jaws to avoid drilling, and both seams simultaneously welded in a welding machine, using two electrodes, to prevent warping.
What I claim is:—
- 15 1. A hollow brake rod formed from a pair of commercial rolled angle bars, said bars having edge to edge engagement and rigidly connected together to form a hollow rod substantially rectangular in cross section, the ends of said angle bars being formed into jaws parallel with the 85
20 plane of said meeting edges and each having a reinforcing flange extending about its edge, the angle portion of each angle bar merging into the jaws at opposite ends of the corresponding bar, bosses on said jaws at each end of said brake 90
25 rod and having aligned apertures therethrough.
30 2. A hollow brake rod formed from a pair of commercial rolled angle bars, the thickness of the metal forming the angular portion of each bar being greater along the bisector of the angle than that of the flange portion, the flanges and corner portions thereof being merged to form said jaws in planes parallel to the weakest neutral axes of said bars, said jaws having relatively flat base portions formed with apertured bosses and marginal flange 95
35 portions, and weld means uniting said bars.

3. A hollow brake rod constructed from a pair of commercial rolled angle bars formed with jaws at their respective ends and having edge to edge engagement in the plane of the neutral axis of the rod and between the bights of the jaws, the thickness of the metal forming the angular portion of each bar being greater along the bisector of the angle than that of the flange portion, the flanges and corner portions thereof being merged to form said jaws in planes parallel to the weakest neutral axes of said bars, the neutral axes of said angle bars, each of said flat portions being provided with inwardly extending apertured bosses and having an inwardly extending flange extending around its edge outwardly of said bosses, the angle portion of each angle bar at each end thereof merging into said jaws.

4. A hollow brake rod constructed from a pair of commercial rolled angle bars formed with jaws at their respective ends and having edge to edge engagement in the plane of the neutral axis of the rod and between the bights of the jaws, the thickness of the metal forming the angular portion of each bar being greater along the bisector of the angle than that of the flange portion, the flanges and corner portions thereof being merged to form said jaws in planes parallel to the weakest neutral axes of said bars, said jaws having relatively flat base portions formed with apertured bosses and marginal flange portions, and weld means uniting said bars.

4. A fabricated hollow brake rod constructed from a pair of commercial rolled angle bars formed with their respective end portions flattened and their intermediate portions complementing each other to form a polygonal column having sides inclined with respect to the plane of and merging with, said flattened end portions to provide jaws having perforated bosses and marginal flange portions beyond the bight of said jaws, the thickness of the metal of the angular portion of each bar along the bisector of the angle being greater than the thickness of the flange portion, and weld means uniting said bars between said bight portions of the jaws.
